CLAIM

The ornamental design for package for oral care products, as shown and described.

DESCRIPTION

FIG. 1 is a perspective view of package for oral care products, showing our design according to the first embodiment;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of package for oral care products, showing our design according to the second embodiment;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of package for oral care products, showing our design according to the third embodiment;

FIG. 16 is a front view thereof;

FIG. 17 is a back view thereof;

FIG. 18 is a left view thereof;

FIG. 19 is a right view thereof;

FIG. 20 is a top view thereof;

FIG. 21 is a bottom view thereof;

FIG. 22 is a perspective view of package for oral care products, showing our design according to the fourth embodiment;

FIG. 23 is a front view thereof;

FIG. 24 is a back view thereof;

FIG. 25 is a left view thereof;

FIG. 26 is a right view thereof;

FIG. 27 is a top view thereof;

FIG. 28 is a bottom view thereof;

FIG. 29 is a perspective view of package for oral care products, showing our design according to the fifth embodiment;

FIG. 30 is a front view thereof;

FIG. 31 is a back view thereof;

FIG. 32 is a left view thereof;

(Continued)

FIG. 33 is a right view thereof;
 FIG. 34 is a top view thereof;
 FIG. 35 is a bottom view thereof;
 FIG. 36 is a perspective view of package for oral care products, showing our design according to the sixth embodiment;
 FIG. 37 is a front view thereof;
 FIG. 38 is a back view thereof;
 FIG. 39 is a left view thereof;
 FIG. 40 is a right view thereof;
 FIG. 41 is a top view thereof; and,
 FIG. 42 is a bottom view thereof.
 The broken lines shown in the drawings depict portions of the package for oral care products that form no part of the claimed design.
